Inventor:
JACOB L. SHROYER
By *Genevieve Rain Hartke* *Attest.*

UNITED STATES PATENT OFFICE.

JACOB L. SHROYER, OF OAK PARK, ILLINOIS, ASSIGNOR OF ONE-HALF TO CHARLES O. HARD, OF SCOTIA, NEW YORK.

FOLDING RECEPTACLE.

Application filed November 19, 1923. Serial No. 675,647.

To all whom it may concern:

Be it known that I, JACOB L. SHROYER, a citizen of the United States, residing at Oak Park, in the county of Cook and State 5 of Illinois, have invented certain new and useful Improvements in Folding Receptacles, of which the following is a specification.

The invention relates to improvements in 10 folding receptacles for toilet use, such for example as wash basins, and the like.

One of the objects of the invention is to provide an insertable in-the-wall dressing case in connection with the wash basin.

15 Another object is to improve the appearance of the device when closed and its utility when open.

Another object is to utilize the space in the frame by provision of a medical cabinet in 20 the upper portion thereof and a cabinet for reception of shoes and the like in the bottom part and the provision of mirrors on the inside and outside of the doors that close the main cabinet.

25 In many respects the device is generally similar to that disclosed in my Patent No. 1,317,829 granted to me October 7, 1919.

Other objects and advantages of the invention will readily appear from a consideration 30 of the following description when taken in conjunction with the accompanying drawings, wherein:

Fig. 1 is an elevation of the device with the doors of the main cabinet closed.

35 Fig. 2 is a substantially central vertical section taken on line 2—2 of Fig. 1.

Fig. 3 is a view similar to Fig. 1 showing the doors open.

40 Fig. 4 is a fragmentary section taken on line 4—4 of Fig. 5.

Fig. 5 is a section taken on line 5—5 of Fig. 4.

Fig. 6 is a front elevation of twin faucets or bibbs.

45 Fig. 7 is a side elevation showing parts in section.

In all the views the same reference characters are employed to indicate similar parts.

The device is, preferably, self contained so 50 that it may be completed in a shop and inserted in an aperture made in the side wall of a room. In this respect it is similar to a structure disclosed in my copending application Serial No. 646,563, filed June 20, 1923.

An outer frame 10 extends from the base-board 11 to and around an ornamental panel 12 and below the panel at 13. The panel is made a part of the structure for ornamental purposes only.

55 Doors 14 and 15 are hinged to the inside edge of the vertical portions of the frame 10 at 16 and swing outwardly on their hinges. They are glazed at 17 in small glass, or other panels. These doors when open serve as screens to protect the side walls of the room against the splash resulting from use of water in the basin, besides serving other useful purposes hereinafter more specifically disclosed.

60 In the lower part of the frame is suitably hinged an outwardly swinging bowl 19 supported by the hinge arrangement 20 specifically described in my copending application Serial No. 646,563, filed June 20, 1923. Each hinge consists of a trunnion 21 secured to the side of the bowl 19 and received in a horizontally elongated slot 22 made thru the fixed plate 23.

65 The arm 24, fixed cam plate 25 and spring 26 cooperate to cause the bowl to be moved outwardly as it is swung on its hinge support for a purpose more fully disclosed in the aforesaid application.

Above the bowl 19, inside the frame, are shelves 27 and 28 to receive and support 70 toilet articles, hair brush and comb and the like. Above the shelves is a cabinet 29, the back wall 30 of which is a part of the frame structure. This cabinet may be used as a medicine cabinet, or the like. The cabinet 75 29 is closed by a door 31 hinged to one side frame member at 32. The front of the door carries a mirror 33 which is to be used in connection with the wash bowl 19.

80 A lower cabinet 34 which may be used to contain shoes or the like is closable by the vertically slidable panel 35. The panel 35 may be raised only when the doors 14 and 15 are open and the bowl is folded in.

85 To water pipes 36 faucets or bibbs 37 are connected to deliver hot and cold water into the bowl 19. A waste pipe 38 having a trap 39 is connected to the hopper 40 under the bowl. The waste pipe passes thru a side opening in the frame 10 and is connected in a waste stack 41 and which is connected to a vent stack 42 by an upwardly inclined pipe 43.

The faucets 37-37' are connected together by a cross tube 41 to the center of which is a downwardly curved discharge spout 42. The rear parts of the hollow stems 43 are closed at 44 and each is provided with two aligning lateral perforations 45 and 46. In the perforation 45 is inserted a pipe 47 closed at its air chamber to prevent water hammer. To the other perforation 46 is connected the water supply pipe 36.

Each faucet 37-37' is provided with a flange 48 to lie against the back wall 30' of the structure and each flange has a perforation 49 by which to attach it to the wall. One of the faucets 37 may be connected to the hot water supply and the other to the cold water supply and the cross tube 41 may serve as a mixing chamber between the two faucets.

Mirrors 44 and 45 on the inside of the swinging doors are very effective in connection with mirror 33 for showing all sides of the upper portion of an observer's body and

are appreciated features of a dressing outfit, as shown.

Having described my invention what I claim as new and desire to secure by Letters Patent, is:—

1. A device of the character described comprising a cabinet divided into three vertically consecutive minor cabinets; a bowl located in the intermediate cabinet and arranged to swing outwardly therefrom; a pair of swinging doors to close the two upper cabinets and a sliding door to close the lower cabinet movable to open position when the swinging doors are open.

2. In a device of the character described, a cabinet, an outwardly swinging water receptacle hinged therein, a door hinged to each vertical member of the cabinet frame to close the upper part thereof and to conceal said receptacle, and a sliding door to close the lower part of said cabinet.

In testimony whereof I hereunto set my hand.

JACOB L. SHROYER.
